(57) **CLAIM**

The ornamental design for an electronic hot air comb, as shown and described.

DESCRIPTION

FIG. 1 is a front elevation view of an electronic hot air combat showing my new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof; and,

FIG. 7 is a perspective view thereof.
